Herbert G. Odum
HIS ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

AIR AND WATER TUBE FOR ROCK DRILLS.

Application filed April 3, 1924. Serial No. 703,868.

To all whom it may concern:

Be it known that I, FRED M. SLATER, a citizen of the United States, and a resident of Easton, county of Northampton, and

State of Pennsylvania, have invented a certain Air and Water Tube for Rock Drills, of which the following is a specification accompanied by drawings.

This invention relates to fluid actuated percussive machines, but more particularly to rock drills of the hammer type which employ concentrically arranged liquid conveying and gaseous fluid conveying tubes for introducing a mixture of liquid and gaseous fluid, such as water and air, into the drill steel for cleansing the drill hole.

In order to cleanse the drill hole, most rock drills of the hammer type employ a tube which extends through the machine and communicates with the hollow drill steel for conveying liquid under pressure, usually water, for washing the cuttings from the drill hole. In order that there may be sufficient pressure upon this water, some of the pressure fluid which is employed for actuating the hammer piston, is usually permitted to escape into the drill steel and mix with the water and thereby create a greater pressure to remove the cuttings. Under some circumstances, however, there is insufficient pressure fluid escaping past the hammer piston to remove the cuttings and two concentrically arranged tubes have been used, one of which is adapted to convey gaseous fluid and the other a liquid. In this manner the amount of pressure fluid introduced into the drill steel may be materially increased, so that the removal of the cuttings from the drill hole may be efficiently effected.

One object of this invention is to enable concentrically arranged gaseous fluid and liquid conveying tubes to be securely held in place in a rock drill of the hammer type by an improved and simplified means.

Further objects of the invention will hereinafter appear and the invention is shown in one of its preferred forms in the accompanying drawings, in which—

Figure 1 is a vertical sectional elevation of a stope drill with some of the parts broken away,

Figure 2 is an enlarged detail sectional elevation of the back head with the concentrically arranged tubes connected thereto, 55

Figure 3 is a reduced sectional elevation of the back head plug showing the manner in which the liquid conducting tube is connected thereto, 60

Referring to the drawings, the invention is shown embodied in a stope drill having a cylinder A to which the front head B is attached by the usual spring pressed bolts (not shown). The percussive element in this instance comprises the piston C having a forward fluted extension D which is adapted to reciprocate in the bore of the cylinder A. The forward fluted extension D of the piston extends through the front cylinder 70 washer E and engages the internal flutes on the chuck F. In this instance an anvil block G is located in the chuck F and is adapted to permit the impact blows of the piston C to the hollow 75 drill steel H which is adapted to extend through the bushing J into the front head B. In this instance, the piston C is provided with a rifle nut K into which the rifle bar L extends and the rifle bar L is preferably formed with a head O, which carries suitable pawls P. The rifle bar head O is located in the ratchet ring Q, which is preferably formed with the ratchet teeth R which are adapted to be engaged by the 80 pawls P. As the piston C reciprocates in the cylinder A, the rifle bar L is permitted to rotate in one direction by the pawls P co-operating with the ratchet teeth R, as the flutes on the forward extension D of the 85 piston C are straight, the piston C is caused to rotate in one direction until this rotation is permitted through the chuck F to the drill steel H so that the drill steel H continually rotates in one direction. The back 90 head or head block S closes one end of the ratchet ring Q and the feed cylinder T is connected to the back head S by side bolts (not shown). A feed piston U having a suitable piston rod and ring engaging pointer (not shown) is slidable in the cylinder T and pressure fluid may be supplied to the feed cylinder T by any suitable means 100 but preferably from the throttle valve V

which is in this instance located in the back head S and is adapted to be manipulated by a suitable valve lever W.

Concentrically arranged tubes X and Y are in this instance held in the back head S and the tube Y, which is preferably inside the tube X, is formed with a nozzle Z which extends through the rifle bar head O, the rifle bar L, piston C and into the anvil block G and is adapted to supply liquid to the hollow bore of the drill steel H. The tube Y is formed with a nozzle Z and the tube X, which is outside the tube Y, also extends through the rifle bar head O, rifle bar L, piston C and a short distance into the anvil block G. A chamber a is preferably provided in the anvil block G between the end of the tube X and the counter bore b in the anvil block into which the nozzle Z of the tube Y extends.

In this instance, both the tubes X and Y are secured to the back head S and for this purpose the back head is formed with a recess c having a counter bore d. The outer tube X is preferably formed with an outwardly flared end portion e, which is adapted to be forced to a tapered seat in the back head S by a suitable plug f through which the tube Y is adapted to extend and which has a tapered end portion g adapted to bear against the flared end portion e. The plug f is preferably provided with a transverse port h which communicates with the hollow bore of the tube X at its center and also communicates with a passage j in the back head S through which a gaseous fluid, such as compressed air, is adapted to be supplied through a port k in the valve V. By manipulating the valve lever W in order to bring the valve port k and the passage j into registration, a gaseous fluid will be supplied to the tube X from which it will pass through the anvil block G and into the hollow bore of the drill steel H.

In order to secure the liquid conducting tube Y in the back head S, an annular collar o is preferably formed on the tube Y adjacent one end thereof and an external screw threaded plug p is formed with a bore q and a counter bore r. One end of the tube Y is, in this instance, adapted to extend a short distance into the counter bore r and the collar o lies in the bore q. A gland s is preferably screwed into the bore q of the plug p and is adapted to bear against the collar o on the tube Y for the driving movement of the tube Y relative to the plug p. An aperture plug t may be inserted in one end of the plug p if desired. The plug p in this instance extends a slight distance beyond the back head S and a cap u is adapted to be screwed onto the plug p and a suitable packing v may be inserted between the cap u and the back head S for forming a fluid tight connection therebetween. In order to

supply liquid to the tube Y, a passage w is preferably formed in the back head S and a longitudinal passage x is preferably formed in the plug p. Liquid, such as water, is adapted to be introduced in the passage w through a suitable inlet connection y and water will flow through the passage w into the longitudinal passage x and into the chamber z formed between the plug p and the cap u and thence through the counter bore r into the tube Y. A suitable packing washer 2 may be interposed between the plug p and the plug f about the tube Y in order to prevent relative movement of the parts and to maintain the tapered portion g of the plug f against the flared portion e of the tube x. The packing 2 is adapted to be tightly pressed against the tube Y by the plug p and in this instance a washer 3 is located between the packing 2 and gland s.

The plug p, the tube Y and the gland s may be removed from the back head S as a unit in order to inspect the tube Y or for any other reason. Although the tubes X and Y are shown connected to the back head S of a stope drill it is to be understood that these tubes may be connected to a rock drill of the drifter type and that any convenient cleansing liquid such as water may be supplied directly to the tube Y through the plug p and this invention is not to be understood as limited to the embodiment shown in the drawings such as defined in the appended claims. It will be observed that the tube X is somewhat shorter than the tube Y and this arrangement enables additional pressure to be created on the liquid flowing from the nozzle Z of the tube Y for effectively cleansing the drill hole. It is preferable that a gaseous pressure fluid be supplied to the tube X slightly before it is admitted to the percussive element in order to keep the drill hole free from the cuttings, although this feature is not essential to the invention.

I claim:

1. In a rock drill, the combination with a cylinder, of percussive means therein, a hollow drill steel, a back head for said cylinder, separate gaseous fluid and liquid conducting tubes communicating with said steel and terminating at their rear ends in said back head, means for removably securing one of said tubes in said back head and a tapered plug adapted to bear against the other of said tubes in said back head.

2. In a rock drill, the combination with a cylinder, of percussive means therein, a hollow drill steel, a back head for said cylinder, separate concentrically disposed gaseous fluid and liquid conducting tubes communicating with said steel and terminating at their rear end in said head, a separate end portion on one of said tubes adapted to seat against said back head, means adapted to co-

operate with said flared end portion for holding said tube in said back head, a plug connected to said back head and means for removably securing the other of said tubes in said plug.

3. In a rock drill, the combination with a cylinder, of percussive means therein, a hollow drill steel, a back head for said cylinder, separate concentrically disposed gaseous fluid and liquid conducting tubes communicating with said steel and terminating at their rear ends in said back head, a tapered end portion on the rear end of one of said

tubes adapted to seat against said back head, a tapered plug having a hollow bore adapted to cooperate with said tapered end portion for holding said tube in place in said back head, a plug in said back head having a hollow bore into which the other of said tubes is adapted to extend and a gland connected to said plug for holding said last mentioned tube in place in said plug.

In testimony whereof I have signed this specification.

FRED M. SLATER.
